UNITED STATES PATENT OFFICE.

JOSEPH OPITZ, OF HAINITZ, SAXONY, GERMANY.

TROUGH FOR WET-SPINNING MACHINERY.

Application filed July 12, 1927, Serial No. 205,198, and in Germany September 9, 1925.

In spinning flax by machines including a water trough, the roving is drawn through a trough filled with warm water at a temperature of about 40-70° C. for the purpose of loosening the long line or tow threads in order to render the threads suitable for drawing between the drawing rollers.

Timber was hitherto used in the construction of this hot water trough. Pine or larch wood posts of about 22 to 25 feet in length, and about 11 inches broad by about 16 inches thick were joined together to form a watertight vessel by grooved and tongued joints or by rabbeting and screwing together with strong wood screws and using red-lead cement as the jointing medium. The whole vessel was then waterproofed with three coats of red lead and varnish. Any knot holes had to be previously bored out, stopped with wooden plugs and made watertight with varnish and red lead cement. With the best selected timber, the very best care in making the trough, and a good red-lead varnish coating, these troughs would sometimes last 20 to 30 years. With careless construction, the life of the trough was much shorter and often the troughs had to be repaired after a few years' use, because the joints became leaky, knots rotted out, the plugs let in water, and resinous parts of the wood decayed.

The water dripping from the leaks naturally affected the durability, wear and efficiency of the spindle driving cords, apart from the fact that the loss of warm water should be avoided as far as possible for obvious reasons.

The present invention consists in constructing these long troughs of metal-reinforced concrete, making them in parts or sections which are joined together. Troughs or sections of a convenient length do not put too much strain on the resistance of the mass to bending and thus enable comparatively long troughs to be made, using for this purpose the aforesaid material which has already been used for various purposes, including troughs.

The trough sections are joined at the ends by means of cast-iron coupling rings with projections and grooves which are secured in the concrete body by means of lugs cast thereon. The longitudinal reinforcements terminate in these rings. The joint is made tight preferably by inserting red lead ce-

ment between the projections and grooves of the coupling rings and tightening-up means of brass coupling screws or bolts.

Such troughs are cheaper than wooden troughs and making them in sections enables trough sections to be kept in readiness for rapid replacement.

The drawing illustrates one constructional example.

Fig. 1 is a transverse section through a metal-reinforced concrete trough according to this invention.

Fig. 2 is a section through the inner end of such a trough made in two halves.

Fig. 3 is a longitudinal section through the middle portion of a two-part trough, showing the parts slightly separated.

The numeral 1 represents the roving which passes through the tube 2 and through the warm water bath over the glass rod 3. 75 Wrought iron angle pieces 4 and 5 are embedded in the concrete trough 19, and upon them the brass bridge pieces 8 are fastened by means of brass screws. The sheet asbestos covers 9 and 10 are strengthened by 80 means of cast-iron bars 12 to prevent them from warping owing to the water temperature in the trough varying from about 10° to 70° C. The covers rest loosely upon the brass bridge pieces 8, but are kept in place 85 in recesses formed by raised parts 18.

The longitudinal reinforcement at the vulnerable parts consists of round iron 6 of about $\frac{1}{4}$ inch diameter and at the other parts consists of strap iron 7. The transverse reinforcement consists of flat iron strips, similar to the longitudinal reinforcement 7.

The glass rod 3 over which the thread is delivered, is fixed in recesses by brass strips 11 at the rim of the trough. 95

At the joints of the two halves of the trough, the brass strips are somewhat wider in order to cover the joint at this part.

According to Figs. 2 and 3, the two halves of such a trough abut at their ends which carry rings 13 adapted to interlock where they abut by means of a groove and feather and are drawn together by bolts 15. The rings are firmly bound to the concrete and reinforcement by means of lugs 14. Iron strips 16 riveted to the bridge pieces 8 serve to further secure the bridge pieces 8 in the concrete wall, whilst iron strips 17 are doubled longitudinal reinforcements which with the lugs 14 tied in the end wall by binding 110

wire, form a metal-reinforced concrete skeleton structure. 20 is a steam pipe.

After tightening the brass bolts, asbestos cord soaked in red lead is wound around the 5 rings to fill the space between the two end walls of the trough sections and the remaining space is filled with plaster of Paris.

Having now particularly described and ascertained the nature of my said invention 10 and in what manner the same is to be performed, I declare that what I claim is:—

1. A trough for use in wet flax spinning comprising reinforced concrete trough sections arranged in longitudinal alinement each 15 trough section being provided with end walls, conducting and coupling rings embedded in the opposed end walls of the trough sections and projecting beyond said walls and provided in their meeting faces with 20 interconnecting means for closing the joint between them, and fastening members for uniting the opposed ends of the trough sections and holding the rings in coupled relation.

25 2. A trough for use in wet flax spinning comprising reinforced concrete trough sections arranged in longitudinal alinement, each trough section being provided with end walls, conducting and coupling rings embedded in the opposed end walls of the trough sections and projecting beyond said walls and provided in their meeting faces with 30 interconnecting means for closing the joint between them, and fastening members for uniting the opposed ends of the trough sections and holding the rings in coupled 35 relation, the rings being of a diameter less than the dimensions of the trough ends and forming cores about which filling material 40 may be placed to close the gap between the trough ends.

3. A trough for use in wet flax spinning comprising reinforced concrete trough sections arranged in longitudinal alinement, each trough section being provided with end 45 walls, conducting and coupling rings embedded in the opposed end walls of the trough sections and projecting beyond said walls and provided in their meeting faces 50 with interconnecting means for closing the joint between them, said rings having lugs embedded in the end walls, and fastening bolts 55 engaging lugs of the rings for uniting the ends of the trough sections and holding the rings in coupled relationship.

4. A trough for use in wet flax spinning comprising reinforced concrete trough sections arranged in longitudinal alinement, each trough section being provided with end 60 walls, conducting and coupling rings embedded in the opposed end walls of the trough sections and projecting beyond said walls and provided in their meeting faces 65 with interconnecting means for closing the joint between them, said rings having lugs

embedded in the opposed end walls of the trough sections, reinforcing members in said walls of the trough sections and fastened to said lugs, and fastening bolts engaging certain of said lugs of the rings for uniting the 70 opposed ends of the trough sections and holding the rings in assembled relationship.

5. A trough for use in wet flax spinning comprising reinforced concrete trough sections arranged in longitudinal alinement, 75 each trough section being provided with end walls, conducting and coupling rings embedded in the opposed end walls of the trough sections and projecting beyond said walls and provided in their meeting faces 80 with interconnecting means for closing the joint between them, said rings having lugs embedded in the end walls and being of less diameter than the dimensions of the walls and forming cores about which filling material 85 may be placed to close the gap between the trough ends, and fastening bolts engaging lugs of the rings for uniting the trough ends and holding the rings in assembled relationship.

90 6. A trough for use in wet flax spinning comprising concrete trough sections arranged in longitudinal alinement and each having longitudinal and transverse reinforcements and end walls, conducting and coupling rings connected to the longitudinal reinforcements and embedded in the opposed end walls of the trough sections and provided with lugs embedded therein, said rings having portions projecting beyond the end 95 walls and provided with interconnecting means for closing the joints between them, reinforcing members embedded in said end walls and connected to the lugs of the rings, and fastening bolts engaging lugs of the 100 rings for uniting the trough ends and holding the rings in assembled relationship.

105 7. A trough for use in wet flax spinning comprising a reinforced concrete trough body including angle metal reinforcing strips along the front and rear edges of said body, bridge pieces extending from front to rear of the body and resting on and secured to said strips, and a cover for the body resting on said bridge pieces and engaged 110 therewith to prevent displacement thereof.

115 8. A trough for use in wet flax spinning comprising a reinforced concrete trough body including angle metal reinforcing strips along the front and rear edges of 120 said body, bridge pieces extending from front to rear of the body and resting on and secured to said strips, and a cover for the body resting on said bridge pieces and engaged therewith to prevent displacement thereof, said bridge pieces and cover having 125 interengaging projections and recess to prevent displacement of the cover.
